United States Patent Office.

ALBERT G. SAFFORD, OF BOSTON, MASSACHUSETTS.

Letters Patent No. 95,938, dated October 19, 1869.

RAILROAD-CAR VENTILATOR.

The Schedule referred to in these Letters Patent and making part of the same.

To all persons to whom these presents may come:

Be it known that I, ALBERT G. SAFFORD, of Boston, of the county of Suffolk, and State of Massachusetts, have invented an Improved Ventilator for Railway-Carriages, or for apartments of various kinds; and I do hereby declare the same to be fully described in the following specification, and represented in the accompanying drawings, of which—

Figure 1 is a front elevation of the ventilator as closed.

Figure 2, an elevation of it as open.

Figure 3, a transverse section of it as open, the section being taken so as to exhibit the stops of the valve of the ventilator.

In the drawings—

A denotes an elliptical valve, arranged within an elliptical opening, B, of like size, and pivoted at its opposite ends, and in the line of its greater axis, to the opposite ends of the said opening, the pivots being represented in dotted lines at *a a*.

Near one of the pivots is a stop-piece, C, which projects from one end of the opening, and is formed in manner as represented in the drawings, its two

edges, *b c*, which make a right angle with each other, serving as stops, to arrest the valve in either a horizontal or a vertical position, or “opened” or “closed,” as the case may be.

At a short distance from the centre of the valve, a round ball or heavy weight, D, is fastened to the valve, and is projected therefrom, in manner as represented. This ball or weight, operating with the stops, serves to maintain the valve either opened or closed, or, in other words, either in a horizontal or in a vertical position.

The gravitating ventilator so made is not only simple in construction, but very efficient in operation, it being specially calculated for the ends of the interiors of street-railway carriages.

I claim the arrangement and combination of the ball D and the stops *b c* with the valve A, its pivots, and the opening B, for reception of the valve, the whole being substantially as set forth.

ALBERT G. SAFFORD.
